UNITED STATES PATENT OFFICE.

ADOLPH G. KAUFMAN, OF NEW YORK, N. Y.

LANTERN-GLOBE-SUPPORT PLATE.

1,230,234.

Specification of Letters Patent. Patented Mar. 27, 1917.

Application filed June 30, 1916. Serial No. 106,773.

To all whom it may concern:

Be it known that I, ADOLPH G. KAUFMAN, a citizen of the United States, residing at New York, in the county and State of New York, have invented a new and useful Lantern-Globe-Support Plate, of which the following is a specification.

This invention relates to lanterns, and especially to lanterns which vaporize a hydrocarbon fluid and burn the same in connection with an incandescent mantle; and the object of the invention is to provide a globe support for such a lantern so constructed that the preheating liquid, as alcohol, can be placed in the preheating cup on the vaporizer in a simple and effective manner and burned in such a way as to utilize the maximum amount of the heat units thereof in heating the vaporizer, or generator.

20 The invention is illustrated in the accompanying drawing, in which—

Figure 1, is an elevation of a lantern, with parts broken away, and part in vertical section, the same being constructed in accordance with my invention;

Fig. 2, is a plan view of the globe support plate mounted on the reservoir, or font; and

Fig. 3, is a fractional view, showing a modified form of construction.

In the drawings, like numerals of reference refer to the same parts in each of the views.

In practice I provide a lantern having a font 4, vaporizer 5, air mixer 6, carrying incandescent mantles 7, an air-intake tube 8, top 9, bail 10, a controlling valve operated by a valve wheel 11, a preheating cup 12, mounted on the vaporizer, as shown, and an inclosing globe of glass 13, as shown in Fig. 1, or a mica globe 13', as shown in Fig. 3.

Either of the above globes is supported on my improved globe support plate 14, which is mounted on the bracket 15, as indicated in dotted lines in Fig. 2, which bracket also supports the lower end of the air-intake tube 8, on which the air mixer is carried in a manner that will be readily understood.

50 The globe support plate 14, is dish-shaped at the center, as shown more particularly in Figs. 1 and 3; and has a central circular opening 16, with a projecting portion 17, at one side thereof providing for the continuation of a channel 18, passing radially from

the central opening in the plate to a raised portion 19, and an annular rib 20. This plate is so held on the bracket 15, that it will be held slightly above the preheating cup 12, to leave a space 21, so that the alcohol in burning in the preheating cup will be carried inwardly around the vaporizer 5, in the form of a cone, and the heat will thus be concentrated on the vaporizer.

As shown the extension, or projection 17, of the plate rests upon the top of the preheating cup; but this is not necessary as the entire plate may be carried on the bracket 15, in a manner to hold the projection 17, slightly above the preheating cup edge. This plate, however, is always so disposed relative to the preheating cup as to leave a space for the air to carry the flame inward as described above; but is not located so high that there is danger of the preheating fluid not flowing into the cup, or that the lantern should not have the utmost compactness.

If a glass globe, as 13, is used, the bottom rests within the annular rib 20, as clearly shown in Fig. 1, leaving the enlarged portion 22, of the channel 18, so that when the preheating fluid is poured into the enlarged part 22, it will flow down the channel 18, beneath the globe 13, into the preheating cup; and the fluid can then be lighted either at the preheating cup, or through the opening covered normally by the pivoted slide door 23, which opening can also be utilized in igniting the gas at the mantles, as will be clear.

Where a mica globe, as 13', is used, the support plate 14, is provided with an annular ledge 24, on which the bottom of the mica globe rests in a secure manner, as shown in Fig. 3. As this ledge is outside of the enlarged part 22, of the channel 18, a port is provided in the side of the mica globe, as shown at 25, through which the spout 26, of a pouring can may be inserted to pour the generating fluid into the channel 18, or the enlarged part 22, thereof.

In making these support plates I always provide both the annular rib 20, and the ledge 24, so that the user can utilize either kind of a globe, as may be desired; and the top 9, is always provided with the engaging rings 27, and 28, to hold either the glass globe, or the mica globe, as will be understood.

As constructed the plate is compact in form, cheap to manufacture, and efficient in use. Alcohol, or any preheating fluid can readily be poured into the preheating cup without disturbing the globe; and the gas can be ignited at the mantles without disturbing the globe, as will be clear.

It is evident that the projecting portion 17, need not be used, and the opening 16, 10 could be made small enough to insure the alcohol flowing into the cup. In that event, however, the plate would have to be raised slightly more above the preheating cup to insure the flame all entering the opening and 15 forming a cone around the vaporizer.

I claim:

1. A lantern having a vaporizer and preheating cup, a support plate mounted above said cup, said plate having a dish-shaped 20 center with a central opening above the cup, and having a channel leading down the said dish-shaped portion to said opening.

2. A lantern having a vaporizer and preheating cup, a globe support plate mounted 25 above said cup, said plate having a dish-shaped center with an opening therethrough above the cup adapted to permit the passage 30 of the vaporizer, said plate having globe-holding means, and a channel leading from 35 said globe-holding means to said central opening, for the purpose set forth.

3. In a lantern, a globe support plate dish-shaped in form with a central opening, said plate having a channel therein extending 35 from a point adjacent to the outer edge to said opening.

4. In a lantern, a globe support plate having a dish-shaped center, a globe-holding rib adjacent to the outer edge, and a channel

passing through said rib to said opening, for 40 the purpose set forth.

5. In a lantern, a globe support plate having a central opening, globe-holding means, and an inclined channel passing from said globe-holding means to said opening. 45

6. In a lantern, a globe support plate having a dish-shaped center with a central opening, a globe-holding rib adjacent to the outer edge, a channel passing through said rib to 50 said central opening, and an enlarged channel portion outside of said rib, for the purpose set forth.

7. In a lantern, the herein described globe support plate comprising a plate stamped to form a central dish-shaped portion with an 55 opening through the center thereof, a channel extending radially from said opening, said channel ending at its outer end in an enlarged portion, a globe-holding rib through which said channel passes, means to 60 secure the plate to a bracket, and an opening at one side of the central opening with means adjacent thereto to pivot a sliding door over said last-named opening.

8. A lantern having a vaporizer with a 65 preheating cup mounted thereon, and having a bracket extending from the font to a point above the preheating cup position, a globe support plate mounted on said bracket 70 above said preheating cup, said plate having an inclined channel therein leading from the outer edge of said plate to the preheating cup, said bracket holding said plate spaced from said preheating cup, for the purpose set forth.

Dated this 29th day of June, 1916.

ADOLPH G. KAUFMAN,
